(57) CLAIM

What is claimed is the ornamental design for a security strap, as shown and described.

DESCRIPTION

FIG. 1 is a perspective view of a security strap, showing the new design;

FIG. 2 is an enlarged left-side elevational view thereof;

FIG. 3 is an enlarged right-side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines in FIG. 5 indicate stitching that forms part of the claimed design.
